US00D518498S

(12) **United States Design Patent** (10) **Patent No.:** **US D518,498 S**
Reed et al. (45) **Date of Patent:** **** Apr. 4, 2006**

(54) **FUSION NIGHT VISION SYSTEM**

(75) Inventors: **Matthew W. Reed**, New Boston, NH (US); **Duncan A. Boyce**, Winchester, MA (US); **Timothy R. Loring**, Bedford, NH (US); **Christopher J. McBride**, Londonderry, NH (US)

(73) Assignee: **Insight Technology, Inc.**, Londonderry, NH (US)

(**) Term: **14 Years**

(21) Appl. No.: **29/219,956**

(22) Filed: **Dec. 22, 2004**

(51) **LOC (8) Cl.** 16-06

(52) **U.S. Cl.** **D16/132**

(58) **Field of Classification Search** ..... D16/132, D16/133, 130, 200, 202, 203, 207, 230; 359/350, 359/362, 353, 399, 405, 407, 409-411, 480-481, 359/631, 430, 809, 819, 418; 250/214 VT, 250/216

CLAIM

The original design for a fusion night vision system, as shown and described.

DESCRIPTION

FIG. 1 is a first perspective view of a fusion night vision system of the present invention;

FIG. 2 is a front view of the fusion night vision system of FIG. 1;

FIG. 3 is a rear view of the fusion night vision system of FIG. 1;

FIG. 4 is a right side view of the fusion night vision system of FIG. 1;

FIG. 5 is a left side view of the fusion night vision system of FIG. 1;

FIG. 6 is a top view of the fusion night vision system of FIG. 1; and,

FIG. 7 is a bottom view of the fusion night vision system of FIG. 1.
